UNITED STATES PATENT OFFICE.

WILLIAM H. MITCHELL, OF ST. LOUIS, MISSOURI.

PERMUTATION-LOCK FOR AUTOMOBILES.

1,261,266.

Specification of Letters Patent.

Patented Apr. 2, 1918.

Application filed February 26, 1917. Serial No. 151,036.

To all whom it may concern:

Be it known that I, WILLIAM H. MITCHELL, a citizen of the United States, residing at St. Louis, in the State of Missouri, have invented certain new and useful Improvements in Permutation-Locks for Automobiles; and I do hereby declare the following to be a full, clear, and exact description of the invention, such as will enable others skilled in the art to which it appertains to make and use the same.

This invention relates to automobiles and has special reference to a permutation lock arranged to simultaneously control the spark circuit of the motor of the automobile and the supply of gasoline to said motor.

More specifically the invention relates to a combined switch and valve for automobiles and the like.

One important object of the invention is to improve the general construction of devices of this character.

A second important object of the invention is to provide an improved form of permutation switch for devices of this character.

A third important object of the invention is to provide an improved form of permutation valve for devices of this character.

A fourth important object of the invention is to provide a valve and switch so constructed and arranged in a novel manner that one permutation indicating device will control both the valve and the switch simultaneously.

With the above and other objects in view, as will be hereinafter apparent the invention consists in general of certain novel details of construction and combinations of parts hereinafter fully described, illustrated in the accompanying drawing, and specifically claimed.

In the accompanying drawing, like characters of reference indicate like parts in the several views, and:—

Figure 1 is a face view of the device with the front removed.

Fig. 2 is an edge view of the device with the casing in section to show the interior.

Fig. 3 is a section on the line 3—3 of 50 Fig. 1.

Fig. 4 is a detail section on the line 4—4 of Fig. 1.

Fig. 5 is a detail view of the upper valve disk.

Fig. 6 is a detail view of the lower valve disk.

Fig. 7 is a section through the valve at right angles to Fig. 3.

Fig. 8 is a view showing the inside of one 60 of the arms used herewith with the spring thereon.

In the embodiment of the invention herein illustrated there is disclosed a casing 10 having a circular flange 11 whereon are 65 mounted a series of stop pins 12 having rounded upper ends 13. Fixed within the casing is an insulating plate 14 and extending through this insulating plate and projecting above the flange 11 is a series of contact pins 15 provided at the bottom with binding screws 16 so that the wires 17 of the spark circuit may be connected to any two or these contact pins at will. These pins 15 are partially inclosed by a plate or the like 75 13'. Extending through the center of the casing and journaled therein is a stub shaft 18 whereon is a sleeve 19, the stub shaft and sleeve being independently rotatable. Projecting from both the stub shaft and the 80 sleeve are arms 20 each having on its lower side a recess 21 adjacent its extremity and each of these arms swings over the pins 12 so that the rounded ends 13 are successively engaged in the recess of the respective arm, 85 the arms being spring arms for the purpose of permitting this engagement and the disengagement of the arms from said pins.

Each of these arms is moreover provided with a button or thumb piece 22 so that it 90 may be moved around the dial and adjacent the pins 12 are permutation numbers or characters 23 to enable the arm to be set to any desired number or character.

Extending from the inner side of each of 95 the arms 20 is a post 24 which is insulated therefrom by means of the washer of insulating material 24' and extending outward

from this post is a spring contact 25 which engages successively with the pins 15 as the arm is moved around the center. The lower extremity of each of the pins 24 contacts with a circular plate 25' of conducting material mounted on the insulating plate 14, said circular plate forming electrical connecting means for the pins 24. It is to be noted that at the time the recess 21 is engaged on any one of the rounded pin ends 13 the spring 25 will be in engagement with a corresponding pin 15.

It is preferred that the pins at the top, bottom and opposite sides of the device be 15 shouldered as at 26 so that they may constitute starting points to enable the device to be set by touch. At 27 is a valve casing having an inlet 28 and an outlet 29. The inlet is connected to the intake or supply 20 pipe 30 from the gasoline tank, not shown, while the outlet is connected to a pipe 31 running to the engine, also not shown. Within the chamber of the valve 27 is a lower valve disk 32 having a port therein 25 which extends downwardly, as at 33, from its upper side and then transversely, as at 34. There is also provided in this chamber an upper valve disk 35 having a notch 36 in one edge. The valve disk 32 is fixed on 30 a shaft 37 which carries a beveled gear 38 meshing with a similar beveled gear 39 fixed on the shaft 18. The valve disk 35 is fixed upon a sleeve 40 which carries a beveled gear 41 meshing with a beveled gear 42 on the 35 sleeve 19.

By this means an operative connection is established between each of the arms 20 and a respective valve disk.

It is to be noted that the valve is provided with the usual bonnet 43 and stuffing 40 box 44 and between the bonnet and the upper valve disk is a coil spring 45 which holds the valve disks firmly together and prevents any flow of gasoline from the 45 pipe 30 to the pipe 31, when the valve is closed. However, when the arms 20 are in the proper position it will be seen that the notch 36 registers with the port 33 and also with the pipe 30 while the port 34 registers 50 with the outlet 29. In this position the contact will also be in engagement with those contact pins which are connected to the wires 17. Thus the circuit for the spark arrangement of the automobile is closed at 55 the same time that the gasoline supply is opened.

In order to prevent observation of the dial when set it is preferred that the front of the casing be closed by a cover 46 hinged 60 to the casing, as at 47, and provided at 48 with a lock preferably of the pin type. Moreover for convenience sake and for the purpose of improving the looks of the device I prefer to make the cover 46 in the

form of a hollow casing wherein may be 65 mounted a clock, the casing of which is indicated at 49 and the front of which is protected by means of a glass plate 50 securely held in the casing forming the front of the device.

From the foregoing it will be obvious that when the hands are set at the proper point the machine may be operated as the spark will be closed and the gasoline turned on. When the operator desires to leave his machine it is merely necessary to open the 75 front of the casing and disarrange the hands from their position of operation whereupon both the spark circuit will be opened and the gasoline cut off. Under these circumstances even if the operator forgets to lock the door of the casing and leaves the hands exposed it will be practically impossible for any person to operate the device as it is intended to have twenty-eight pins in the contact pin series so that there will be seven hundred and fifty-six combinations.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such as properly come within the scope claimed.

Having thus described the invention, what is claimed as new is:—

1. In a device of the character described, an insulating disk, a contact plate on said disk and adapted to be connected to an electric ignition circuit, inner and outer series of pins supported concentrically of said plate, certain of the inner pins having electrical connection with the circuit, independently movable arms rotatably supported centrally of the disk and releasably engageable with the inner and outer pins, stud members carried by and insulated from the arms and frictionally engaging the plate and resilient contacts on the stud members and parallel with the arms to frictionally wipe the inner pins on movement of said arms for the closing of the circuit when said contacts engage with certain of said pins.

2. In a device of the character described, a casing having a closing at its front, an annular flange interiorly of said casing, an insulating disk carried by said flange, a contact plate on said disk and adapted to be electrically connected with an ignition circuit, inner and outer series of pins on the flange and disk, respectively, concentrically of the plate, certain of the inner pins having electrical connection with the circuit, certain of the outer pins being formed with

reduced ends, independently movable arms rotatably supported centrally of the disk and releasably engageable with the inner and outer pins, stud members carried by and 5 insulated from the arms and frictionally engaging the plate and resilient contacts on the stud members and parallel with the arms to frictionally wipe the inner pins on movement of said arms for the closing of the circuit when said contacts engage with cer- 10

tain of said pins, each of the arms being formed with recesses in its under face to receive the ends of the inner and outer pins.

In testimony whereof I affix my signature in the presence of two witnesses.

WILLIAM H. MITCHELL.
